CARRIER-SIGNAL SELECTOR NETWORK

Benjamin F. Tyson, Bayside, N. Y., assignor to
Hazeltine Corporation, a corporation of Del-
aware

Application October 8, 1940, Serial No. 360,249

7 Claims. (Cl. 178—44)

The present invention relates to an improved selector network adapted to translate a plurality of carrier signals and, particularly, to a selector network having a plurality of predetermined distinct band-pass characteristics any one of which may be selected substantially to the exclusion of the others. While the invention is of general application, it has particular utility as a selector network between successive stages of intermediate-frequency amplification of a superheterodyne receiver and will, therefore, be described in that connection.

Conventional carrier-signal receivers adapted to operate over a plurality of carrier-signal frequency bands generally employ a single fixed intermediate frequency usually between 170 and 470 kilocycles. This intermediate frequency provides satisfactory image rejection when the receiver is operating in the low-frequency carrier-signal bands, but does not provide entirely satisfactory image rejection in the higher-frequency bands, the image rejection becoming increasingly poor as the signal frequency increases.

In order that the image-rejection characteristic of the receiver shall be more nearly uniform over the entire frequency range of the receiver, it is desirable that different intermediate frequencies be employed for different ones of the frequency bands. The selection of a particular intermediate frequency is preferably accomplished by a switching arrangement operated simultaneously with the radio-frequency band selector of the receiver. In general, an intermediate frequency of 465 kilocycles is satisfactory for frequency bands up to 20 megacycles and an intermediate frequency of 2,250 kilocycles is satisfactory for the frequency bands extending from 20 megacycles up to 100 megacycles. The use of a plurality of intermediate frequencies has the additional important advantages that tuning of the receiver is greatly facilitated, the detrimental effect of frequency drift of the local oscillator is minimized, and the larger separation of oscillator frequency and signal frequency in the higher-frequency bands makes for greater ease in aligning the receiver by decreasing the drag of the oscillator-tuned circuit on the radio-frequency circuits of the receiver, or vice versa, due to incidental coupling between these circuits.

For the purpose of ensuring that the gain of the receiver shall be uniformly high at each intermediate frequency employed, it is desirable that an individual intermediate-frequency selector be provided for each one of the several intermediate frequencies. Each selector thus may

have individual and different band-pass characteristics suitable to provide the desired over-all band-pass characteristic for each of the several intermediate frequencies. Any one of the several 5 intermediate-frequency selectors is selectively chosen by an appropriate switching arrangement. The switching systems heretofore employed for this purpose have been unduly complex and, therefore, relatively expensive or have not been altogether satisfactory in enabling the attainment of the required plurality of intermediate-frequency amplifier band-pass characteristics.

It is an object of the present invention, therefore, to provide a new and improved selector network which, while of general application, is especially suitable for use in coupling successive stages of intermediate-frequency amplification and one which avoids one or more of the above-mentioned disadvantages and limitations of the 20 prior art devices.

It is a further object of the invention to provide an improved selector network having a plurality of predetermined distinct frequency band-pass characteristics any one of which is effectively selected substantially to the exclusion of the others by the selective operation of a simplified 25 and improved switching system.

In accordance with one embodiment of the invention, a selector network adapted to translate 30 a plurality of carrier signals comprises a pair of input terminals and a pair of output terminals, and a plurality of transformers permanently connected in series and coupled between the input and output terminals. The selector network also 35 includes means for imparting to each of the transformers a predetermined different carrier-frequency band-pass characteristic for translating a different one of the carrier signals, and there is included in the selector network a single 40 switch for short-circuiting all but a selected one of the transformers effectively to suppress the transmission between the input and output terminals of all other carrier signals except the carrier signal which the one transformer is adapted to translate.

For a better understanding of the present invention, together with other and further objects thereof, reference is had to the following description taken in connection with the accompanying drawing, and its scope will be pointed out in the appended claims.

Referring now to the drawing, Fig. 1 is a circuit diagram, partly schematic, of a complete carrier-signal receiver embodying the invention;

and Fig. 2 is a circuit diagram representing a modified form of the invention.

Referring now more particularly to Fig. 1, there is represented schematically a complete carrier-signal receiver of a conventional design embodying the present invention in a preferred form. In general, the receiver includes a radio-frequency amplifier 10 having its input circuit connected to an antenna system 11, 12 and having its output circuit connected to an oscillator-modulator 13. Connected in cascade with the oscillator-modulator 13, in the order named, are an intermediate-frequency amplifier 14 more fully described hereinafter, a detector and automatic amplification control or A. V. C. supply 15, an audio-frequency amplifier 17 of one or more stages, and a sound reproducer 18. The radio-frequency amplifier 10 and oscillator-modulator 13 are adapted to operate over a plurality of frequency bands any one of which may be selected by operation of wave band switches conventionally represented at 19 and 20. The A. V. C. bias derived by the unit 15 is applied to the input circuit of the radio-frequency amplifier 10, the oscillator-modulator 13, and the intermediate-frequency amplifier 14 in conventional manner.

It will be understood that the various units just described may, with the exception of the intermediate-frequency amplifier 14, be of a conventional construction, the details of which are well known in the art, rendering detailed description thereof unnecessary. Considering briefly the operation of the receiver as a whole, and neglecting for the moment the operation of the intermediate-frequency amplifier 14 presently to be described, a desired carrier signal in one of the frequency bands selected by the band-change switches 19, 20 is received and amplified by the radio-frequency amplifier 10, converted to an intermediate-frequency carrier signal in the oscillator-modulator 13, amplified in the intermediate-frequency amplifier 14, and detected by the detector 15 thereby to derive the audio-frequency modulation components. The audio-frequency components are, in turn, amplified in the audio-frequency amplifier 17 and are reproduced by the sound reproducer 18 in a conventional manner. The automatic amplification control supply of unit 15 operates in a conventional manner to maintain the signal input to the detector within relatively narrow limits for a wide range of received signal intensities.

Referring now more particularly to the portion of the system embodying the present invention, the intermediate-frequency amplifier 14 includes an input selector network 21 and an output selector network 22 each adapted to translate a plurality of intermediate-frequency carrier signals. These selector networks are essentially similar in construction and operation and only one, therefore, will be considered in detail; similar circuit elements of each network are designated by similar reference numerals except that elements of the network 22 are distinguished from those of the network 21 by prime numerals. The selector network 21 has a pair of input terminals 23, 24 and a pair of output terminals 25, 26. A plurality of intermediate-frequency transformers 27, 28 have their respective primary windings 29, 30 permanently connected in series across the input terminals 23, 24 and their respective secondary windings 31, 32 permanently connected in series across the output terminals 25, 26 and thus are permanently connected in series and coupled between the input and output

terminals. In order selectively to short-circuit either of the primary windings 29 or 30 thus effectively to short-circuit all but one of the transformers, there is provided means comprising a single-pole switch 33 having a switch blade connected to the junction of the primary windings 29, 30 and having switch contacts individually connected to opposite terminals of the transformer primary windings. There are connected across the input terminals 23, 24 and the output terminals 25, 26 respective condensers 37 and 38. Upon operation of the switch 33 to close its lower contact, condenser 37 tunes the primary winding 29 of transformer 27 to a first intermediate frequency while the condenser 38, together with the capacitive effect of the transformer secondary winding 32 and a condenser 41 connected in parallel thereto, tunes the secondary winding 31 of transformer 27 to the same intermediate frequency. The condensers 37 and 38 thus comprise capacitive means individually connected across the input and output terminals effectively to tune one of the transformers, specifically the transformer 27, to the frequency of a predetermined one of the carrier signals applied to the selector network 21 upon the selection of such one transformer by the switching means 33. A resistor 39 may be connected across the primary winding of transformer 27 to aid in imparting to this transformer a predetermined carrier-frequency band-pass characteristic. Permanently connected across the primary winding 30 and secondary winding 32 of transformer 28 are respective condensers 40 and 41. Upon closure of the switch 33 to its upper contact, the condenser 40 aids the condenser 37 in tuning the primary winding 30 of transformer 28 to its own individual intermediate frequency while the condenser 41, together with the capacitive effect of the transformer secondary winding 31 and condenser 38, tunes the secondary winding 32 of transformer 28 to the same intermediate frequency. The condensers 40 and 41 thus comprise means individual to the transformer 28 and effective with the aforementioned capacitive means comprising condensers 37 and 38 to tune the latter transformer to the frequency of an individual one of the applied carrier signals upon selection by the short-circuiting or switching means 33 of such latter transformer. The condensers 37, 38, 40 and 41 and the resistor 39 comprise means for imparting to each of the transformers 27, 28 a predetermined different carrier-frequency band-pass characteristic for translating a different one of the plurality of carrier signals applied to the selector network 21.

The intermediate-frequency amplifier 14 includes a vacuum-tube repeater 42 having input electrodes coupled to the output terminals 25, 26 of the input selector network 21 and output electrodes coupled to the input terminals 23', 24' of the output selector network 22. The repeater 42 is suitably energized from sources of operating potential +B and +Sc. The switches 33 and 33' of the respective networks 21 and 22 are connected for unicontrol operation with the wave band switches 19 and 20 of the radio-frequency amplifier 10 and oscillator-modulator 13, as indicated by the broken line 43.

In considering the operation of the circuit just described, it will be assumed that the wave band switches 19 and 20 of the radio-frequency amplifier 10 and oscillator-modulator 13 are positioned for operation of the receiver over a lower-frequency band, for example, the broadcast band

of frequencies from 500 to 1,500 kilocycles, and that the transformers 28 and 28' are connected in circuit by operation of their respective switches 33 and 33' to close their upper contacts. It will further be assumed that the output of the oscillator-modulator 13 has a relatively low intermediate frequency, for example, 456 kilocycles, to which the transformers 28 and 28' are tuned. The switches 33 and 33' now short-circuit the respective transformer primary windings 29, 29', whereby the intermediate-frequency transformers 27, 27' are effectively short-circuited and removed from circuit. The intermediate-frequency amplifier 14 consequently operates in conventional manner to translate intermediate-frequency carrier signals within the pass band of the transformers 28, 28' and effectively to suppress all other intermediate-frequency carrier signals. The over-all transmission band-pass characteristic of the amplifier 14 is, under the assumed conditions, determined solely by the band-pass characteristics of the transformers 28, 28'.

Upon movement of the wave band switches 19 and 20 to select a higher-frequency band over which the receiver is to be operated, as, for example, a frequency band above 20 megacycles, the switches 33, 33' are simultaneously moved, by virtue of their mechanical connection with the wave band switches, to close their lower contacts. The transformer primary windings 30, 30' are thereupon short-circuited, whereby the transformers 28, 28' are effectively removed from circuit, and the transformers 27, 27' are connected in circuit in the intermediate-frequency amplifier 14. At the same time, the operation of the switch 20 to its new position has the result that the intermediate frequency now produced in the output of the oscillator-modulator 13 has a relatively high frequency, for example, 2,250 kilocycles, to which the transformers 27, 27' are tuned. The operation of the intermediate-frequency amplifier 14 is again conventional in every respect except that it translates intermediate-frequency carrier signals of the new intermediate frequency and effectively suppresses the transmission of all other intermediate-frequency signals. The over-all transmission characteristic of the intermediate-frequency amplifier 14 is now determined solely by the individual band-pass characteristics of the transformers 27, 27'.

The selector network of the invention thus comprises two tuned transformers having primary windings, selected by switches, which are resonant at either of two carrier-signal frequencies and a secondary circuit which is simultaneously resonant at both these frequencies, thereby to provide two selectable band-pass characteristics having maximum transmission at two carrier-signal frequencies. The network also has a minimum transmission characteristic at a carrier-signal frequency lying between the two frequencies of maximum transmission. In selecting the values of the circuit constants of the selector network, the values of the transformer primary windings 29 and 30 and the condensers 37 and 40 are computed in conventional manner, the value of the condenser 37 preferably being made as small as possible consistent with permissible small changes of capacitance resulting from tube replacements, temperature variations, etc., in order that the voltage-transfer ratio of the transformers 27 and 27' should be high. Having chosen suitable values for the condensers

37 and 40, the condensers 38 and 41 may arbitrarily be given the same respective values and the values of inductances of the transformer secondary windings 31 and 32, and the minimum transmission frequency, are given by the following equations:

$$C_2 = \frac{(f_1^2 - f_2^2 + f_3^2)^2}{(f_3^2 - f_2^2)(f_2^2 - f_1^2)} C_1 \quad (1)$$

$$L_3 = \frac{1}{4\pi^2(f_1^2 - f_2^2 + f_3^2)C_1} \quad (2)$$

$$L_4 = \frac{f_1^2 - f_2^2 + f_3^2}{4\pi^2 f_1^2 f_3^2 C_2} \quad (3)$$

where,

C_2 =the capacitance of condenser 41,

C_1 =the capacitance of condenser 38,

L_3 =the inductance of the transformer secondary winding 31,

L_4 =the inductance of the transformer secondary winding 32,

f_1 =the carrier-signal frequency to which transformer 28 is tuned,

f_2 =the frequency of minimum response of the selector network, and

f_3 =the carrier-signal frequency to which the transformer 27 is tuned.

Fig. 2 is a circuit diagram representing a modified form of the invention essentially similar to that of the Fig. 1 embodiment except that the selector network of this modification is adapted to translate more than two intermediate-frequency carrier signals. Circuit elements of the Fig. 2 arrangement corresponding to similar circuit elements of the Fig. 1 arrangement are designated by similar reference characters and analogous circuit elements by the same reference numerals double-primed. In this modification, a transformer 44 has a primary winding 45 which is permanently connected in series with the primary windings 29 and 30 of the respective transformers 27 and 28 across the input terminals 23, 24 and has a secondary winding 46 which is permanently connected in series with the secondary windings 31 and 32 across the output terminals 25, 26 of the selector network. The transformer 44 is tuned by a condenser 47 and by a condenser 48 with other of the capacitive effects of the secondary circuit elements to an intermediate frequency different from those to which the transformers 27 and 28 are tuned. A resistor 49 is connected across the primary winding 45 to aid in imparting to transformer 44 a predetermined carrier-frequency band-pass characteristic. The switch 33'' is slightly different from the corresponding switch of the Fig. 1 arrangement in that it has a pair of segments 50, 51 which rotate together, each of the segments being of sufficient length to engage any three adjacent switch contacts. The switch has four equally-spaced contacts 52-55, contacts 52 and 55 being individually connected across the input terminals 23, 24, contact 53 being connected to the junction of the primary windings of transformers 27 and 44, and contact 54 being connected to the junction of the primary windings of transformers 44 and 28. The switch 33'' is uni-controlled with the wave band switch of the receiver as indicated by the broken line 43.

The operation of this modification of the invention is essentially similar to that of the Fig. 1 embodiment, the switch 33'' short-circuiting all but a selected one of the transformer primary

windings thereby effectively to short-circuit all but one of the transformers 27, 28, or 44. The selective network thus transmits the carrier signal which the selected transformer is adapted to translate and effectively suppresses the transmission of all other carrier signals.

From the foregoing description of the invention, it will be evident that a selector network embodying the invention has a plurality of predetermined distinct frequency band-pass characteristics any one of which is effectively selected substantially to the exclusion of the others by the selective operation of a single switch of simple and inexpensive construction comprising a minimum of switch contacts. Each of the frequency band-pass characteristics of the selector network may be adjusted and shaped quite independently of other of the band-pass characteristics since individual groups of elements provide a given band-pass characteristic and operate quite independently of other groups of elements of the selector network.

While the switches 33, 33' and 33'' are arranged to short-circuit selected ones of the transformer primary windings, it will be evident to one skilled in the art that, as an alternative and equivalent arrangement, the switches could equally well be arranged to short-circuit selected ones of the transformer secondary windings.

While there have been described what are at present considered to be the preferred embodiments of this invention, it will be obvious to those skilled in the art that various changes and modifications may be made therein without departing from the invention, and it is, therefore, aimed in the appended claims to cover all such changes and modifications as fall within the true spirit and scope of the invention.

What is claimed is:

1. A selector network adapted to translate a plurality of carrier signals comprising, a pair of input terminals and a pair of output terminals, a plurality of transformers permanently connected in series and coupled between said input and output terminals, means for imparting to each of said transformers a predetermined different carrier-frequency band-pass characteristic for translating a different one of said carrier signals, and a single switch for effectively short-circuiting all but a selected one of said transformers effectively to suppress the transmission between the said input and output terminals of all of said applied carrier signals except the carrier signal which said one transformer is adapted to translate.

2. A selector network adapted to translate a plurality of carrier signals comprising, a pair of input terminals and a pair of output terminals, a plurality of transformers having primary windings permanently connected in series across said input terminals and secondary windings permanently connected in series across said output terminals, means for imparting to each of said transformers a predetermined different carrier-frequency band-pass characteristic for translating a different one of said carrier signals, and a single switch for effectively short-circuiting all but a selected one of said transformers effectively to suppress the transmission between the said input and output terminals of all of said carrier signals except the carrier signal which said one transformer is adapted to translate.

3. A selector network adapted to translate a plurality of carrier signals comprising, a pair of input terminals and a pair of output terminals,

a plurality of transformers having primary windings permanently connected in series across said input terminals and secondary windings permanently connected in series across said output terminals, means for imparting to each of said transformers a predetermined different carrier-frequency band-pass characteristic for translating a different one of said carrier signals, and a single switch for short-circuiting all but a selected one of said transformer primary windings effectively to short-circuit all but one of said transformers to suppress the transmission between the said input and output terminals of all of said carrier signals except the carrier signal which said one transformer is adapted to translate.

4. A selector network adapted to translate a plurality of carrier signals comprising, a pair of input terminals and a pair of output terminals, a pair of transformers having primary windings permanently connected in series across said input terminals and secondary windings permanently connected in series across said output terminals, means for imparting to each of said transformers a predetermined different carrier-frequency band-pass characteristic for translating a different one of said carrier signals, and a single-pole switch having a switch blade connected to the junction of one of said pairs of series-connected windings and switch contacts individually connected to opposite terminals thereof, whereby either of said one transformer windings may be selectively short-circuited effectively to short-circuit one of said transformers to suppress the transmission between the said input and output terminals of all of said applied carrier signals except the carrier signal which the other of said transformers is adapted to translate.

5. A selector network adapted to translate a plurality of carrier signals comprising, a pair of input terminals and a pair of output terminals, a pair of transformers having primary windings permanently connected in series across said input terminals and secondary windings permanently connected in series across said output terminals, means for imparting to each of said transformers a predetermined different carrier-frequency band-pass characteristic for translating a different one of said carrier signals, and a single switch having a switch blade connected to the junction of said primary windings and switch contacts individually connected to the opposite terminals thereof, whereby either of said primary windings may be short-circuited effectively to short-circuit one of said transformers to suppress the transmission between the said input and output terminals of all of said carrier signals except the carrier signal which said other transformer is adapted to translate.

6. A selector network adapted to translate a plurality of carrier signals comprising, a pair of input terminals and a pair of output terminals, a plurality of transformers having primary windings permanently connected in series across said input terminals and secondary windings permanently connected in series across said output terminals, means for effectively short-circuiting all but one of said transformers, capacitive means individually connected across said input and output terminals effectively to tune one of said transformers to the frequency of a predetermined one of said carrier signals upon the selection of said one transformer by said last-named means, and capacitive means individual to each of the other of said transformers and effective with said first-named capacitive means to tune each of said

other transformers to the frequency of a different one of said carrier signals upon the selection by said short-circuiting means of others of said transformers.

7. A selector network adapted to translate a plurality of carrier signals comprising, a pair of input terminals and a pair of output terminals, a plurality of transformers having primary windings permanently connected in series across said input terminals and secondary windings permanently connected in series across said output terminals, means for effectively short-circuiting all but a selected one of said primary windings, ca-

5 pacitive means individually connected across said input and output terminals effectively to tune one of said transformers to the frequency of a predetermined one of said carrier signals upon the selection of said one transformer by said last-named means, and capacitive means individual to each of the other of said transformers and effective with said first-named capacitive means to tune each of said other transformers to the frequency of a different one of said carrier signals upon the selection by said short-circuiting means of others of said transformers.

BENJAMIN F. TYSON.
